UNITED STATES PATENT OFFICE.

JOHN E. FISHER, OF NEW YORK, N. Y.

AIR-PUMP.

SPECIFICATION forming part of Letters Patent No. 758,516, dated April 26, 1904.

Application filed May 15, 1901. Renewed September 10, 1903. Serial No. 172,571. (No model.)

To all whom it may concern:

Be it known that I, JOHN E. FISHER, a citizen of the United States, residing in New York, borough of Manhattan, in the State of New York, have invented certain new and useful Improvements in Air-Pumps, of which the following is a specification.

This invention relates to certain improvements in air-pumps, and more particularly to improvements in that class of air-pumps which are adapted for use by cyclists for inflating cycle-tires; and the object of the invention is to provide a conveniently-operated air-pump in which all the parts are compactly held together for being carried in the pocket or tool-bag and which is of simple construction, so that it can be supplied at a low price.

For this purpose the invention consists in the combination, in an air-pump with a handle-section, of a telescoping foot-section provided at its outer end with a backwardly-turned portion located beyond the side of the handle-section and a flexible connecting-tube connected with said backwardly-bent portion and adapted to lie alongside said handle-section.

In the accompanying drawings, Figure 1 represents a side elevation of my improved air-pump, showing the parts in position for use. Figs. 2 and 3 are respectively side and front elevations of the air-pump, showing the same folded up after use, so as to be carried in the tool-bag of the cycle. Fig. 4 is a detail vertical central section through portions of the cylinder or handle-section, piston-rod, and piston; and Fig. 5 is a horizontal section through the handle-section on the same scale as Fig. 4.

Similer letters of reference indicate corresponding parts.

Referring to the drawings, A represents the handle-section or cylinder of my improved air-pump, which is closed at one end and provided at the opposite end with a detachable screw-cap a. In the handle-section A is arranged the piston B, which is preferably composed of a tubular shank b, having a flange or washer b' secured thereto at its inner end, and a packing b², of leather or other suitable material, secured in position on the flange by means of a screw b³, which is screwed into the

shank b and provided with a perforation b⁴ for the passage of the air from the space in the cylinder below the packing into the tubular shank b. To the shank b is secured, by soldering or otherwise, the tubular piston-rod 55 C, which is free to move through the cap a and which is bent outside of the cylinder back toward the same, as shown at c, said bend being preferably semicircular and the backwardly-turned portion being located beyond 60 the side of the handle-section. To the portion c', which is threaded for the purpose, is applied the connection d of the usual flexible connecting-tube D, the opposite end of which is provided with a nipple d' for attachment to 65 the valve of the tire to be inflated. To the bend c is pivoted, as by means of a keeper e' provided with eyes at opposite sides, a U-shaped foot-piece E. The foot-piece is preferably bent of wire of suitable strength, and its outer end is turned up at an angle, so as to 70 form a short bent portion e or clamp of approximately the width of the tube D, as shown, which engages with and serves for retaining the connecting-tube D alongside the 75 tubular handle-section A when the pump is folded up for being carried in the tool-bag of the cycle.

The size of the bend c is such that when the pump is collapsed, as in Fig. 2, the portion c' of the piston lies close to the cap a and body of the cylinder at the side of the latter, so that the flexible tube D is without injurious bend when not in use.

When the air-pump is to be used, connection of the nipple d' is made with the valve of the tire and the foot-piece is swung in the direction of the arrow in Fig. 2 into position shown in Fig. 1, so as to be at right angles to the tubular piston-rod, which latter rests by 90 its bend c upon the ground. The foot of the user is then placed on the foot-piece, while the cylinder is moved up and down by hand upon the piston and piston-rod, so that the air is drawn into the cylinder through the 95 opening a' of the cap, whence it passes the flange b' and packing b² and is expelled through the perforation b⁴, shank b⁵, piston-rod C, tube D, and the tire-valve into the tire. When the tire is inflated, the tube D is disconnected, the 100

piston-rod forced into the cylinder up to the end of the same, as in Fig. 2, and the foot-piece swung over and placed alongside the cylinder, so that the bend at its outer end 5 grips the tube. The entire pump may then be placed in the tool-bag.

When the parts are in the position shown in Fig. 2, the foot-piece and tube D serve each for retaining the other in position, for the 10 reason that the tube D is flexible and not pivoted, while the foot-piece is stiff and pivoted eccentrically to the connection of the tube D with the portion c' of the piston, and the bent end c frictionally engages the tube D.

15 The advantages of my improved air-pump are, first, that the same is composed of few parts, so that it can be readily manufactured at a comparatively low price; secondly, that the connecting-tube is always connected with 20 the piston-rod, so as to be instantly ready for use without requiring to be screwed onto the same; thirdly, that the foot-piece serves for holding the connecting-tube in straight condition alongside of the cylinder when the air-pump is folded up after use.

Having thus described my invention, I claim as new and desire to secure by Letters Patent—

1. In an air-pump, the combination, with a handle-section, of a tubular piston-rod located 30 in the same and provided at its outer end with a backwardly-turned portion located beyond the side of the handle-section, and a flexible connecting-tube connected with said backwardly-turned portion and adapted to lie

alongside said handle-section, substantially as 35 set forth.

2. In an air-pump, the combination, with a handle-section, of a tubular piston-rod located in the same and provided at its outer end with a backwardly-turned portion located beyond 40 the side of the handle-section, a flexible connecting-tube connected with said portion and adapted to lie alongside said handle-section, and a foot-piece pivoted to said piston and having its outer end bent into a clamp of approximately the size of the tube, substantially as set forth.

3. In an air-pump, the combination, with a handle-section, of a tubular piston-rod located in the same and provided at its outer end with 50 a backwardly-turned portion located beyond the side of the handle-section, a flexible connecting-tube connected with said portion and adapted to lie alongside said handle-section, and a foot-piece pivoted to said piston and 55 having its outer end bent into a clamp of approximately the size of the tube, said foot-piece being pivoted to said piston eccentrically to the connection of the flexible tube with the same, substantially as set forth.

In testimony that I claim the foregoing as my invention I have signed my name in presence of two subscribing witnesses.

JOHN E. FISHER.
